United States Patent Office

Des. 221,797
Patented Sept. 7, 1971

221,797

RING

Robert H. Annesley, Houston, Tex., assignor to
Stuckey and Speer, Inc., Houston, Tex.

Filed Sept. 10, 1970, Ser. No. 24,940

Term of patent 14 years

Int. Cl. D11—01

U.S. Cl. D45—10

FIG. 1 is a top plan view of a ring showing my new design;

FIG. 2 is a sectional view on line 2—2 of FIG. 1;

FIG. 3 is a front elevational view; and

FIG. 4 is a side elevational view.

I claim:

The ornamental design for a ring, as shown.
